DESIGN FOR A DOLL

Frankie L. McCulloch, Branson, Mo.

Application October 28, 1935, Serial No. 59,503

Term of patent 7 years

To all whom it may concern:

Be it known that I, Frankie L. McCulloch, a citizen of the United States, residing in Branson, in the county of Taney and State of Missouri, have invented a new, original, and ornamental Design for a Doll, of which the following is a specification, reference being had to the accompanying drawing, forming a part thereof.

I claim:
The ornamental design for a doll, as shown.

FRANKIE L. McCULLOCH.
